CLAIM

The ornamental design for a wrist band, as shown and described.

DESCRIPTION

FIG. 1 is a perspective view of an embodiment of the wrist band;

FIG. 2 is another perspective view of the embodiment;

FIG. 3 is another perspective view of the embodiment;

FIG. 4 is another perspective view of the embodiment;

FIG. 5 is a bottom view of the embodiment;

FIG. 6 is a top view of the embodiment;

FIG. 7 is a right side view of the embodiment, the left side view being a mirror image thereof; and,

FIG. 8 is a front view of the embodiment, the back view being a mirror image thereof.

The broken lines immediately adjacent the shaded areas represent the bounds of the claimed design while all other broken lines are directed to environment and are for illustrative purposes only; the broken lines form no part of the claimed design.
